UNITED STATES PATENT OFFICE.

MALCOLM SCOUGALE, OF FORT WORTH, TEXAS.

INTERMESHING WIRE FABRIC.

No. 890,878.

Specification of Letters Patent.

Patented June 16, 1906.

Application filed August 26, 1904. Serial No. 222,344.

To all whom it may concern:

Be it known that I, MALCOLM SCOUGALE, a citizen of the United States, residing at Fort Worth, Texas, have invented certain new and useful Improvements in Intermeshing Wire Fabrics for Fences and Like Objects, of which the following is a specification.

This invention relates to a new and useful manufacture, and more particularly to a fabric composed of cross-pieces, such as wires, rods, or bars, and the object is to provide an article of manufacture for various purposes, such as screens, fences, cages, and similar structures requiring light and strong and durable fabric.

Other objects and advantages will be fully explained in the following description and the invention will be more particularly pointed out in the claim.

Reference is had to the accompanying drawings which form a part of this application and specification.

Figure 1 is a plan view of a portion of wire fabric, illustrating the manner of weaving the fabric. Fig. 2 is a cross section of the same on a larger scale.

Similar characters of reference are used to indicate the same parts throughout the several views.

The improved fabric is composed of spiral cross pieces woven together. These pieces may be of wire, rods, or bars, or other suitable pieces woven together in the manner hereinafter described. The cross pieces may be formed into spirals before being woven together. The cross pieces running in one direction may be formed into spirals as they are being fed to the machine for weaving the fabric. The thickness through the fabric will be equal to the combined length of the diameters of the cross pieces. The size of the mesh or openings through the fabric is determined by the flight of the spiral and the size of the cross pieces. The inward and

outward sweep or bend of the spiral piece of 45 the different cross pieces alternate with each piece.

The fabric is illustrated by spirals 1, 2, 3, 4, 5, 6, 7, and 8 running in one direction, and spirals 9, 10, 11 and 12 woven into the spirals 50 first mentioned.

The outward sweep or bend of a horizontal piece must engage the inward sweep of a vertical piece and vice versa, and the outward sweep of a vertical piece must engage the 55 inward sweep of a horizontal piece and vice versa. The spreading of the mesh is effectively prevented by the spirals of the cross-pieces, and particularly by the interlocking of the inward and outward sweeps or bends 60 of the cross pieces, as above described.

The advantage of the construction herein described is that the mesh will remain just as it is woven together without any ties or tie wires or clamps of any kind. The cross wires 65 intermesh by reason of a bend in one wire meeting the head of the crossing wire. In intermeshing, the two wires form a tie because the curvature of the two wires permits the two wires to lap more or less together and 70 thus brace each other.

Having fully described my invention, what I claim as new and desire to secure by Letters Patent, is,—

As an article of manufacture, a fabric composed of crossed spiral wires woven together, the respective spiral wires forming a fabric having a thickness of approximately twice the thickness of each intersecting wire, said wires crossing at substantially the center of 80 the bends of the engaging wires.

In testimony whereof, I set my hand in the presence of two witnesses, this 28th day of June, 1904.

MALCOLM SCOUGALE.
